(57) **CLAIM**

The ornamental design for a combination padlock, as shown and described.

DESCRIPTION

FIG. 1 is a front, right, and bottom perspective view of a combination padlock showing my new design.

FIG. 2 is a rear, left, and top perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines illustrate portions of the combination padlock that form no part of the claimed design.

1 Claim, 8 Drawing Sheets
